UNITED STATES PATENT OFFICE.

NICOLAUS AUGUST OTTO, OF COLOGNE, ASSIGNOR TO THE GAS-MOTOREN-FABRIK-DEUTZ, OF KÖLN-DEUTZ, GERMANY.

MOTOR-ENGINE WORKED BY OIL-VAPOR.

SPECIFICATION forming part of Letters Patent No. 433,806, dated August 5, 1890.

Application filed March 1, 1890. Serial No. 342,197. (No model.) Patented in Belgium February 5, 1890, No. 89,416; in Switzerland February 8, 1890, No. 1,874, and in Italy February 25, 1890, LII, 479.

To all whom it may concern:

Be it known that I, NICOLAUS AUGUST OTTO, a citizen of Prussia, residing at Cologne, in the German Empire, have invented 5 new and useful Improvements in Motor-Engines Worked by Oil-Vapor, (for which I have obtained a patent in Belgium, dated February 5, 1890, No. 89,416; Italy, dated February 25, 1890, Vol. LII, 479, and Switzerland, dated February 8, 1890, No. 1,874,) of which the following is a specification.

This invention relates to that description of four-stroke-cycle petroleum-motor engines constructed by me, in which a spray or vapor of petroleum mixed with air to form an explosive compound is introduced through a long heated passage into the working-cylinder, such explosive charge, after compression, being ignited by suitable means in the said 15 passage. The charge, which may be introduced either under pressure or by forming a partial vacuum in the cylinder during the suction-stroke, and which may be formed either in the heated passage itself or before 20 entering the same, effects the clearance of the passage from the residual products of combustion of the previous charge which are retained in the cylinder, and leaves the passage filled with explosive compound suitable 25 for ignition. In the arrangement of such engines heretofore employed by me the whole of the air-supply required for the perfect combustion of the explosive charge was introduced through the long passage, whereby 30 the ignition was rendered more or less uncertain. According to the present invention I obviate this disadvantage by introducing into the passage at the point where the petroleum spray or vapor is introduced only a 35 portion of the air required for the complete combustion, the remaining portion being introduced either directly into the cylinder itself or into the end of the long passage which adjoins the cylinder. By this means 40 the passage remains filled with rich explosive mixture which will ignite with certainty. In four-stroke-cycle petroleum-motor engines in which, after the expelling-stroke, the com-

pression-space remains filled with products of combustion, the explosive charges consisting of a mixture of petroleum-spray and air which is ignited in the passage through which it is introduced, I have observed that if the charge introduced through this passage be a mixture of such a nature that the ignition 55 is always effected instantaneously and with certainty no complete combustion of the entire charge will be effected. If, on the other hand, an explosive mixture be introduced which has such a proportion of air as to insure 60 its complete combustion, then the ignition of the charge will be uncertain and irregular. With explosive mixtures that are readily ignited a complete combustion can no doubt be insured by the employment of 65 devices such as have been frequently proposed for gas-motor engines, whereby the residual products of combustion are replaced by air during the expelling-stroke. The explosive charge then drawn in by the suction- 70 stroke, being in this case introduced into a sufficient body of air instead of into products of combustion, its complete combustion will be effected. This mode of operating, however, I consider not an advantageous one, for several 75 reasons. Independently of the fact that the engine is rendered considerably more complicated by the necessary employment of a compression-pump and a receiver, the disadvantage arises that the oil spray, instead 80 of entering among the hot combustion products, passes into cold or slightly warmed air, thus preventing the fine subdivision of the spray by its conversion into vapor. This is proved by the fact that if, when the engine 85 is running idle, fresh air be drawn into the cylinder through the open escape-valve, instead of drawing back the hot combustion products, the ignition of the subsequent combustible charge is always uncertain. Now my 90 before-described method of operating whereby a readily-ignitable mixture is drawn into the inlet and ignition passage, while at the same time a separate charge of air is introduced directly into the cylinder in which the residual combustion products are allowed to re-

main, is much simpler and at the same time of much greater effectiveness than the above-mentioned method.

The arrangement employed for carrying out my said method of operating may be variously modified. Thus the additional charge of air can be admitted directly into the cylinder through a special valve, or a portion of the air admitted through the valve in the igniting-passage may be led through a separate passage into the cylinder.

It is of advantage to draw in the explosive mixture during the whole of the suction-stroke, or at least during the greater part thereof, as by such extended drawing in a finer degree of the spraying of the petroleum is effected.

The accompanying drawings show, by way of example, one construction of oil-motor engine operating according to the above-described method.

Figure 1 shows a longitudinal section, Fig. 2 a side view, Fig. 3 a cross-section through the air-valve F and escape-valve H, Fig. 4 an end view, Fig. 5 a section showing the circulating-pump, and Figs. 6 and 7 enlarged details, of the oil spraying and mixing apparatus.

A is the cylinder, whose piston B, when in its backward or inward position, leaves a charging or compressing space, with which the uncooled supply and igniting passage C communicates. The charging-space also communicates with the escape-valve H, Fig. 3, and with the air-supply valve F. The curved passage C has an opening at Z for the introduction of a suitable igniting device, such as a heated tube. At its extremity is the valve E for the admission in the form of spray of the oil or other combustible liquid, (shown to a larger scale at Fig. 6, as also the self-acting air-valve D.) The air-supply is admitted to this valve through the regulating-cock M, either immediately from the surrounding atmosphere or through a suitable appliance for lessening noise. There is also provided a gas-supply cock N for admitting ordinary combustible gas on starting the engine.

A pressure-regulator T is provided on the top of the cylinder for supplying the oil under constant pressure to the valve E, the regulator being charged with oil from the upper reservoir S through the pipe U and inlet-valve U', controlled by a float U².

Fig. 2 shows a side elevation of the cylinder, showing the valve-gear and governing apparatus. These mechanisms are worked by the way-shaft K, which revolves at half the speed of the engine-shaft.

Fig. 3 shows a cross-section of the cylinder, and Fig. 5 the construction of a pump for the cooling-water, with special arrangement for regulating the supply of the cooling-water.

The mode of working the engine (shown at Figs. 1 to 6) and of the mechanisms combined therewith is as follows: The oil passing from the tank S and pipe U to the pressure-regulator T and regulating screw-valve O is in the

first instance subjected to a preparatory heating in the space above the spraying-valve E. As soon as the air-valve D opens automatically against the pressure of its spring at the commencement of the suction-stroke, and the valve-stem m is pressed down by the cam k and lever t, the oil is distributed in the small channels p in the enlarged part of the stem m (shown more clearly in the enlarged plan, Fig. 7) and is further divided on contact with the valve-seat, and is then converted into spray by the jet of air entering through valve D into chamber D' and issuing with considerable velocity from the annular nozzle Q. The petroleum-spray thus formed mixes with another supply of air issuing through the nozzle Q', forming an easily-inflammable mixture, and passes through the heated passage C into the cylinder A, where it mixes with the residual products of combustion. During the suction-stroke the air-valve F is opened by the cam l and lever u, thereby admitting to the charge in the cylinder a quantity of fresh air for the above-described purpose. On the return-stroke of the piston the charge is compressed and the compressed charge is then fired in the passage C, effecting the working-out stroke by the consequent expansion. On the following return-stroke the products of combustion are expelled through the escape-valve H, which is opened, by means of the lever e and cam f. The annular nozzles Q and Q' are formed with such restricted area that when the piston B commences its suction-stroke a partial vacuum will be formed in the cylinder, thus enabling the external atmospheric pressure to force the air through the nozzles Q and Q' with considerable velocity and thus produce, first, the effectual spraying of the oil, and, secondly, the intimate and uniform admixture thereof with the air to form the combustible charge entering the cylinder.

The formation of an easily-inflammable mixture is effected by regulating the oil-supply by means of the regulating device O, and the air-supply by the cock M. The air-supply drawn directly into the cylinder A can be regulated either by an earlier or later opening of the valve or by more or less restricting the passage. The valve F can therefore be made to open automatically against the action of a spring, and the valve D may be worked by a lever and cam instead of automatically.

The ignition is effected as nearly as possible at the end of the charging-passage C—such as at the point Z—by means of any suitable igniting appliance. In the drawing Fig. 4 an incandescent igniting-tube is supposed to be employed for this purpose.

The regulation of the engine is effected in such a manner that when, owing to a reduction of the work performed, the engine tends to run at higher speed than the normal the oil-supply is cut off, so that no explosions take place, while at the same time the escape-

valve H is held open, so that the hot products of combustion that are expelled during the expelling-stroke are drawn in again from the discharge-flues during the following suction-stroke, whereby any detrimental cooling of the cylinder-sides is prevented. For the above purpose the regulating-sleeve L, which is moved to and fro by means of the lever e, that works the escape-valve, and by the link 10 g and lever h, is held in its one end position corresponding to the opening of the escape-valve H by the action of the governor b, lever c, and notch d, so that the cams k and l revolve out of gear with the levers t and u, in consequence of which the oil-valve E and the air-valve F are kept closed in a similar manner to that described in the previous application, Serial No. 338,115, filed January 25, 1890. This method of regulation can also be applied 15 to the supply of cooling-water to the cylinder-jacket for the purpose of economizing such water, as shown at Fig. 5. For this purpose the lever e is arranged to force open the suction-valve by means of the rod a, levers n 20 and n', and stem o, which passes through the suction-valve casing and is held down by a spring, such forcing open being effected during the time that the lever e is being acted upon by its cam—that is to say, during about one- 25 fourth of a revolution of the way-shaft. As the pump-eccentric is so placed on the way-shaft relatively to the escape-valve cam f that the said lifting of the suction-valve corresponds to the automatic upward motion of 30 the valve during the suction-stroke of the pump, it will be seen that when the engine is working at the normal speed the said action of the stem o will not affect the working of the pump; but as soon as owing to an 35 increase of speed above the normal the governor causes the escape-valve to be kept open in the above-described manner the suction-valve of the pump will also be kept open, and consequently no water will be supplied to the 40 cylinder-jacket during the time that the supply of oil spray through valve E and of air through valve F is cut off. This mode of regulating the supply of cooling-water has the effect of maintaining the temperature of 45 the engine-cylinder as constant as possible.

If the cooling-water is supplied from a service-pressure pipe, the arm of the escape-valve lever e is made to act directly upon a check-valve in the supply-pipe opening downward and held closed by a spring, so that as long as the escape-valve of the engine is closed

the lever holds the check-valve open and water flows to the cylinder-jacket; but as soon as the escape-valve is held open by the lever e, through regulating mechanism, as above described, the check-valve is closed by means of its spring and by the pressure exerted upon it by the water in the main, so that during such time the water-supply will be stopped.

I do not herein claim the combination, in a four-stroke-cycle petroleum-motor engine, of an ignition or explosion chamber of restricted area at the end of the cylinder communicating at the front end freely with the cylinder and having an inlet-valve for oil with an inlet-valve for air, an igniting device, and a second valve for the introduction of air situated in the cylinder beyond the explosion-chamber, as such features with other combination of elements described and shown herein constitute the subject-matter of my application for patent filed March 1, 1890, Serial No. 342,198.

Having thus described the nature of my invention and the best means I know for carrying the same into practical effect, I claim—

1. In a four-stroke-cycle petroleum-motor engine having an ignition and explosive chamber of restricted area at the end of the engine-cylinder, the method of insuring a reliable ignition and complete combustion of the charge by introducing during the whole or a portion of the suction-stroke a readily-inflammable explosive mixture of petroleum spray or vapor and air through the said ignition and explosion chamber into the cylinder, such explosive mixture being mixed in the cylinder with the residual products of combustion and with a further quantity of air introduced into the cylinder at a point beyond the explosion-chamber, substantially as described.

2. In a four-stroke-cycle petroleum-motor engine, the method of stopping the supply of cooling-water to the cylinder by keeping open the suction-valve of the pump every time the supply of combustible charges is stopped, substantially as and for the purposes described.

In testimony whereof I have signed my name to this specification, in the presence of two subscribing witnesses, this 12th day of February, A. D. 1890.

NICOLAUS AUGUST OTTO.
